UNITED STATES PATENT OFFICE.

WILLIAM F. FREEMAN, OF ELMBROOK, AND STANLEY G. SMITH, OF DETROIT,
MICHIGAN.

DAVENPORT CONSTRUCTION.

Application filed January 30, 1922. Serial No. 532,586.

To all whom it may concern:

Be it known that we, WILLIAM F. FREEMAN and STANLEY G. SMITH, citizens of the United States of America, residing at Elmbrook, Wyoming Township, and the city of Detroit, in the counties of Kent and Wayne and State of Michigan, have invented certain new and useful Improvements in Davenport Construction; and we do hereby declare the following to be a full, clear, and exact description of the invention, such as will enable others skilled in the art to which it appertains to make and use the same.

This invention relates to a davenport bed construction which in unfolded position may be used as a bed and in folded position serves the purposes of a couch or sofa. The present invention is primarily concerned in many novel and useful improvements made in the structure shown in United States Letters Patent, No. 1,260,988, issued March 26, 1918, to make the same more simple and practically operative. In the structure shown in said prior patent, the operation from folded to unfolded position was effected by a crank and necessitated drawing the device out from the wall of the room where it was located, this being objectionable for many reasons. With the present invention, the same broad principle of operation and basic structure is retained but the operation is much more simple and effective no additional operating mechanism being needed, as the free edge of the upper movable section of the device may be grasped and the same turned from open to closed position and vice versa by exerting the required force to accomplish the movements. A further object of the invention is to so construct the davenport that any position to which the movable parts may be moved is retained, it being possible to leave the davenport either wholly or partly open with assurance that it will stay in any position to which moved, this being advantageous in many cases in airing bedding and the like. Further objects of the invention are to simplify the structure as much as possible and reduce the cost of manufacture to a minimum, at the same time making the operation very easy through a counterbalancing spring which counteracts the force of gravity in the raising and lowering of the parts. All of these features, together with

many others not at this time specifically set forth, will appear fully and in detail as understanding of the invention is had from the following description, taken in connection with the accompanying drawings, in which,

Fig. 1 is an end elevation and sectional view of the davenport in folded position, one end frame member thereof being removed to show the operating structure.

Fig. 2 is a like view, showing the davenport in unfolded position.

Fig. 3 is a fragmentary plan and horizontal sectional view of one end of the davenport in unfolded position.

Fig. 4 is an enlarged fragmentary elevation, partly in section illustrating the parts in partly unfolded position.

Fig. 5 is a vertical transverse section through the davenport in folded position, showing the spring construction used.

Fig. 6 is a similar view with the davenport unfolded.

Fig. 7 is a longitudinal vertical section taken substantially on the plane of line 7—7, of Fig. 6, looking in the direction indicated by the arrow.

Fig. 8 is a side elevation with parts broken away, showing the adaptation of the invention to railway seats, as in Pullman cars.

Fig. 9 is a fragmentary enlarged rear elevation of the latching means used to releasably hold the davenport members together in folded position, and

Fig. 10 is a side elevation thereof.

Like reference characters refer to like parts in the different figures of the drawings.

The ends of the davenport include spaced apart outer and inner vertical boards 1 and 2 which at their front edges are connected together and covered by vertical uprights 3. The ends are spaced apart the desired distance and connected together by bottom horizontal cross rails 4 and a lower vertical front rail 5, as shown. A horizontal cross rail 6 extends between the ends at the rear and a distance above the rear bottom rail 4, above which the back 7 to the davenport is positioned, the same being of any suitable construction. An upper finishing arm 8 covers the upper edges of the boards 1 and 2 and extends between them. This makes the frame upon which the folding structure is mounted, the ends being hollow

for the housing of the immediate mounting means therefor.

On the rear side of each upright 3 an angle bar 9 is secured vertically from the rearwardly projecting leg of which a plurality of spaced apart pins 10 extend. A channel 11 is spaced a short distance from the bar 9, paralleling the same and being rigidly connected therewith by bars 12. A short stud shaft 13 is located at the inner end of each of the side bars 14, which together with a connecting cross bar 15 make up the frame for the upper davenport section and within which spring structure 16, similar in most respects to that shown in United States Letters Patent No. 1,363,538, issued Dec. 28, 1920, is secured. In practice, two plates 17 and 18 are permanently secured, one on the inner and the other on the outer side of the inner end of each bar 14, and the shaft 13 is permanently secured thereto projecting therefrom and passing through a vertical slot 20 in the adjacent inner side 2 of the davenport end, as shown in Fig. 3. The shaft at each end of the davenport passes between the bar 9 and channel 11 and is equipped with a roller 21 at its end which bears against the inner flange of the channel 11. A disk 22 formed for a part of its circumference with a segmental gear 23 is fixed to each shaft 13 and the gear teeth are designed to engage with the pins 10 of the adjacent angle bar 9.

The under davenport member comprises a frame made up of two spaced apart side pieces 24 connected at their rear ends by a cross piece 25. Within this frame a spring construction 26 is mounted, being of the usual coiled spring type. A plate 27 is permanently secured at the front end and on the outer side of each frame side piece 24 and each has a bracket 28 permanently secured thereto on which a roller 29 is mounted so as to run on the outer flange of the channel 11. Rollers 29 are located below rollers 21 and the inner board 2 of each end of the davenport is vertically slotted for the passage of the brackets 28 as is obviously necessary to allow for vertical movements of the brackets.

A bell crank lever is loosely mounted on each stud shaft 13 closely adjacent the plate 27 which is also loosely mounted on the shaft as shown in Fig. 3. The bell-crank lever comprises two arms 30 and 31, the former normally extending substantially vertical and the latter to the rear and slightly downward. A link 32 is connected at one end to arm 31 and at its other end has connection with one end of a coiled spring 33 lying alongside the sides 24 of the under davenport member, the rear ends of the springs 33 being secured to brackets 34 permanently secured to said sides 24. A pin 35 projects from each plate 18 and

in the rearward turning movement of the upper davenport member strikes arm 30 of the bell-crank lever, thereby turning the same and stretching the spring at each end of the davenport. 70

In the operation of the davenport, with the parts as shown in Fig. 1, it is merely necessary to grasp the rear edge of the upper davenport member and turn it about the axis of shafts 13 to unfold the davenport 75 to the position shown in Fig. 2. As soon as the movement starts, the gear segments acting on the pins 10 serve to simultaneously elevate shafts 13 and attached parts, whereby the rear under davenport member 80 rises vertically as the upper member is turned forward. This movement is assisted by springs 33, the same being stretched and acting through the bell-crank levers on pins 35 to help the rotation and consequent elevation of the parts. This continues until the upper member has reached substantially vertical position, after which such assistance is not desirable or necessary. When the davenport is fully unfolded, supporting legs 90 for the outer portion of the upper member drop to position, as shown in Fig. 2. To mount these legs brackets 36 are secured one to each side 14 of the upper davenport member, each bracket including two outwardly 95 projecting stops 37, between which the legs 38 are pivotally mounted, limiting the swing of the legs to substantially ninety degrees so that the same automatically assume a horizontal position when the davenport is 100 folded, and a vertical position for support when it is unfolded.

The spring construction for the upper davenport member includes a consecutive series of angle bars 39 pivotally connected 105 together at their ends and so constructed that the same may bend downward when the davenport is in folded position but will be rigid against downward movement when the upper davenport member is reversed in 110 position as when it is unfolded, this being fully disclosed in the former Patent No. 1,363,538, to which reference has been made. One end of the bar structure is loosely mounted in open brackets 40 on the cross 115 piece 15. At the opposite end all of the flexible bar constructions 39 are secured to a rod 41 which at its ends is connected by chains 42 to eye members 43 secured to the inner plates 17, as shown in Fig. 7. The 120 central portion of the rod 41 has a sleeve 44 connected therewith from which wires or cables 45 extend toward members 43, being connected thereto by coiled springs 46.

A mattress 26^a lies above the coiled spring structure 26 and a similar mattress 16^a lies under the spring structure 16 when the davenport is folded, lying above the same when the davenport is unfolded. A covering piece of fabric, leather, or the like is 130

attached at one edge to the upper davenport member above the spring structure and extends therefrom to under the front portion of the lower davenport member, as indicated 5 at 47. A cushion 48 may be secured above the upper davenport member when it is in folded position, the same being removed when the davenport is unfolded.

With this construction, the coiled springs 10 in the spring structure 16 serve as spring cushions for the davenport in folded position and also as a spring support for the mattress 16^a when the davenport is unfolded, the spring 26 similarly supporting 15 the mattress 26^a. This permits the use of coiled springs in a davenport for use both when it is used as a sofa or couch and when it is used as a bed.

It will be noted that the positions of the 20 rollers 21 and 29 is such that the weight of the under davenport member 24 with or without any additional weight thereon serves to practically hold and secure the said under member in any position to which 25 it is moved, there being a binding action of the rollers against the opposite flanges of the channel 11. This permits the davenport being left partly open and insures that it will stay in any such position to which 30 moved, an advantage in airing bedding used without necessitating fully opening the davenport. It also obviates adding any auxiliary supporting means for the under member when it is elevated to lie in alinement 35 with the upper member with the unfolding of the davenport.

The construction described is particularly adapted for use with car seats, as shown in Fig. 8, which are to be used at night for 40 sleeping berths. The construction may be applied to each of two seats 49 facing each other and very quickly and easily opened outward so that the two upper members of the davenport construction come together, 45 making a continuous horizontal mattress support at the upper side, as shown. One of the pieces 15 may carry detachable connecting and securing means 50 of any desired construction to tie the adjacent upper 50 members together when unfolded.

In Figs. 1, 2, 9 and 10, I have shown a releasable latch for holding the two davenport members together when in folded position. A spring latch member 51 is secured 55 to the rear side 25 of the lower member and is adapted to spring over the end 52^a of a bar 52 secured to the rear side (in folded position) of the upper member, automatically latching the members together when 60 they are folded together. A push rod 53 is slidably mounted on and through ears 52^b and 52^c projecting from bar 52, the rod being normally elevated by spring 54, but easily pushed down by engaging with the 65 upper head on the rod, the lower end there-

upon engaging the latch member 51 and moving it to release the upper davenport member, as is obvious.

The davenport construction described is practical, easily operated, relatively simple 70 and economical to manufacture, and particularly serviceable in all respects. The appended claims define the invention and we consider ourselves entitled to all forms of construction coming within their scope. 75

We claim:

1. A davenport comprising two spaced apart ends, a channel and an angle bar located at the front part of each end in vertical spaced apart relation, said angle bar carrying a plurality of pins in spaced apart vertical relation, two short shafts extending between said channel and angle bars, one at each end of the davenport, a gear member fixed to each shaft and engaging 85 with said pins, a roller on the outer end of each shaft bearing against the forward flange of the channel member, a lower davenport member connected with and loosely mounted on and between said shafts 90 at the upper front corners thereof, an upper davenport fixed to and located between said shafts at the upper rear corners thereof, and a roller mounted on the lower davenport member at each end thereof and at the 95 lower front portions to bear against the rear flange of the channels, substantially as described.

2. A davenport comprising two spaced apart ends, a rack bar secured vertically at 100 the front portion of each end, a second bar vertically positioned a short distance back of the rack bar, a short horizontal shaft extending between said bars at each end of the davenport, a gear member fixed to each shaft 105 and engaging with the adjacent rack bar, a roller on the outer end of each shaft bearing against the front side of the adjacent second bar, a lower davenport member loosely mounted on and located between said shafts, 110 being connected thereto at the upper front corners thereof, an upper davenport member fixed to and located between said shafts, having connection thereto at the upper rear corners thereof, and a roller mounted on each end of the lower davenport member at 115 the lower front portions thereof and bearing against the rear side of the adjacent second bar, substantially as described.

3. A construction containing the elements 120 in combination defined in claim 2, combined with a bell-crank lever loosely mounted on each shaft adjacent the gear member fixed thereon, said lever comprising two arms located substantially at right angles 125 to each other, one of said arms normally extending backward alongside of the end of the lower davenport member, a coiled spring attached at one end to the end of said davenport member and connected at its other end 130

to said arm, the other of said arms normally extending vertically, and a pin projecting from each end of the upper davenport member so as to engage said other arm when the upper member is folded over the lower member of the davenport.

4. A davenport comprising upper and lower davenport members located between the ends of the davenport frame, a rack 10 mounted vertically adjacent the front of each end of the frame, a gear in mesh with each rack, means for connecting the gears to the ends of the upper davenport member adjacent the upper rear corners thereof when it is in unfolded position, means to suspend 15 the lower member adjacent the upper front corners thereof and operatively connect it with the gears whereby it will move upwardly or downwardly as the gears traverse the racks upwardly or downwardly, and means connected to the lower davenport member at the front portions of each end thereof coacting with means secured rigidly

on the ends of the frame for holding the davenport members in any position to which 25 operated, substantially as described.

5. A davenport including a frame having spaced apart ends, upper and lower davenport members mounted thereon and located between said ends of the frame, means for 30 operatively connecting the said members and mounting the same on the ends of the frame whereby on turning the upper member forward and outward to horizontal position the lower member is automatically 35 elevated into the same plane therewith, a bar fixed vertically on each end of the frame, and two rollers connected to the lower frame member at each end to bear against opposite sides of the bar, the rollers at the 40 front sides of the bars being located at points higher than those bearing against the rear sides of said bars, substantially as described.

WILLIAM F. FREEMAN.
STANLEY G. SMITH.
